(57) **CLAIM**

The ornamental design for a mobile battery as shown and described.

DESCRIPTION

FIG. 1 is a top perspective view of an embodiment of the present invention;

FIG. 2 is a front elevation view of the embodiment of FIG. 1;

FIG. 3 is a back elevation view of the embodiment of FIG. 1;

FIG. 4 is a left side view of the embodiment of FIG. 1;

FIG. 5 is a right side view of the embodiment of FIG. 1;

FIG. 6 is a top view of the embodiment of FIG. 1; and,

FIG. 7 is a bottom view of the embodiment of FIG. 1.

In the figures, features illustrated in broken line are not part of the claimed design.
